METHOD OF PREPARING VALUABLE HYDROCARBON PRODUCTS FROM ACID SLUDGE

Frederick W. Sullivan, Jr., Hammond, Ind., assignor to Standard Oil Company (Indiana), Chicago, Ill., a corporation of Indiana

No Drawing. Application May 30, 1930,
Serial No. 457,672

3 Claims. (Cl. 196—148)

This invention relates to a method of refining petroleum hydrocarbons and it pertains particularly to the production of high viscosity oil and the hydrogenation of acid sludge residue.

Many petroleum oils (mixed base oils) contain asphaltic, naphthenic, and/or unsaturated compounds which may be hydrogenated to increase their value. However, high viscosity lubricating oils cannot be satisfactorily produced by hydrogenation because heavy oils tend to crack at hydrogenation temperatures. The object of my invention is to obtain high viscosity oils from petroleum and at the same time to hydrogenate at least a portion of the asphaltic, naphthenic and/or unsaturated hydrocarbons.

A further object is to provide a simple process for removing sulfur, sulfuric acid and related compounds, such as sulfonic acids, sulfuric esters, etc. whereby the sludge may be hydrogenated with a minimum amount of hydrogen and without injury to the catalyst.

In my process I treat a mixed base petroleum with sulfuric acid and I separate the resulting oil layer from the acid sludge. I finish the oil from the oil layer and obtain therefrom a high viscosity lubricating oil. I heat the acid sludge to remove the water, sulfur, sulfuric acid and sulfuric acid compounds, the sulfur being removed in oxidized form. Finally, I hydrogenate the viscous material which has been produced from the acid sludge. The invention will be more clearly understood from the following description of a preferred embodiment.

A Mid-Continent crude oil may be heated in a conventional pipe still and fractionated in accordance with conventional practice, and/or it may be reduced with steam so that cracking is prevented. The residue, which may be 40% reduced crude, is then treated with strong sulfuric acid. This treatment comprises agitating the oil with acid (about 93%), using about one-half pound of acid per gallon of reduced crude. The oil is then allowed to settle, the sludge is withdrawn, and the oil is given another treatment, the number of treatments or "dumps" of acid used depending upon the nature of the reduced crude and the desired characteristics of the finished oil.

The effect of such successive treatments on the properties of the final lubricant made from a low grade lubricating stock is shown in the following table. (This refers to a stock corresponding approximately with S. A. E. grade 20. The figures given under "Temperature Viscosity Index" are 55 the viscosity index according to Dean and Davis,

under which Pennsylvania oils have a coefficient of 100).

Acid used (100%) lbs./gal.	Sludge loss percent	NPA color after 5 days at 210° F.	Temperature viscosity index	5
0.47	8.0	6	49	
1.85	34.5	+2½	72	
2.60	47.5	-2½	82	

10 A great improvement in the final quality with heavy acid treatment will be noted, but due to excessive sludge loss such treatment has not previously been economically feasible. The present process, by the recovery of valuable products from 15 the sludge, makes such heavy acid treatment possible.

The oil layer from the above treatment is finished in the conventional manner; mahogany acids are extracted, and the oil is separated from 20 wax and preferably contacted with adsorbent clay at high temperatures to yield a high viscosity lubricating oil.

The sludge from the above treatment is heated in an open vessel, pipe still, and/or any other 25 means to a temperature of about 400 or 500° F. This heat treatment decomposes sulfonic acid, sulfuric acid and sulfuric esters. The sulfur is removed in the form of sulfur dioxide, and the water is removed as steam. The resulting product is a viscous substance of complex molecular 30 structure. By hydrogenating this substance I may obtain lubricating oils of relatively high viscosity together with lighter oil products.

The hydrogenation may be carried out in any 35 conventional apparatus by the use of any conventional catalyst. It should be noted that the complete removal of sulfur and sulfuric acid by heat treatment prevents the sulfuric acid or acid compounds from injuring the catalyst in the hydrogenation step and it should also be noted that I remove a large amount of sulfur in oxide form which would otherwise require hydrogen for converting it into hydrogen sulfide. By removing sulfur in oxidized form I effect a marked economy 40 in the consumption of hydrogen.

45 Wherever herein reference is made to the use of some given amount of "100% acid", it is understood to be not specifically limited to the use of acid of that particular concentration, but to 50 refer to the use of an amount of acid of some convenient concentration equivalent in amount to the stated amount of 100% sulfuric acid.

I claim:

1. The method of preparing valuable hydrocar-

55

- bon products from acid sludges formed in the treatment of petroleum with sulphuric acid, which comprises heating the sludge to a temperature between 400 and 500° F. whereby sulphur and sulphuric acid compounds are largely removed from the sludge without substantial formation of coke, and then subjecting the heated sludge to treatment with hydrogen in the presence of catalytic materials to produce viscous lubricating oil and lighter oil products therefrom.
2. The method of obtaining large yields of valuable lubricating oil from mixed base petroleums which comprises treating the petroleum with about one-half pound of concentrated sulfuric acid per gallon of petroleum whereby an oil layer and sludge are produced, recovering the oil layer from the sludge, heating the sludge to a temperature between 400° F. and 500° F. whereby sulfur and sulfuric acid compounds are removed therefrom without substantial formation of coke, and then subjecting the heated sludge to treatment with hydrogen in the presence of catalytic materials to hydrogenate asphaltic, naphthenic and unsat-

urated compounds therein whereby a further quantity of valuable lubricating oil is obtained.

3. Process for producing large yields of high quality lubricating oil from mixed base petroleum which comprises treating a lubricating oil fraction of said petroleum several successive times with about one-half pound of concentrated sulfuric acid per gallon of said fraction whereby separate oil and sludge layers are produced, separately withdrawing and recovering the oil layers 10 after each treatment and finishing them to a high quality lubricating oil, heating the sludge to a temperature between 400° F. and 500° F. whereby sulfur and sulfuric acid compounds are removed therefrom as oxygen compounds of sulfur without substantial formation of coke, then subjecting the heated sludge to treatment with hydrogen in the presence of catalytic materials to produce a hydrogenated viscous lubricating oil and blending the oil initially separated from the sludge with 15 the hydrogenated oil.
